(57) **CLAIM**

We claim the ornamental design for the skateboard, as
shown and described.

DESCRIPTION

FIG. 1 is a front-top-right perspective view of a skateboard
according to a first embodiment of the present application;

FIG. 2 is a rear-top-right perspective view thereof;

FIG. 3 is a right-side view thereof;

FIG. 4 is a left-side view thereof;

FIG. 5 is a front view thereof;

FIG. 6 is a rear view thereof;

FIG. 7 is a top view thereof;

FIG. 8 is a bottom view thereof; and,

FIG. 9 is a rear-top-right perspective view thereof with an
optional handle shown in broken lines.

The broken lines shown in the drawings depict environment
or portions of the skateboard that form no part of the claimed
design.

1 Claim, 6 Drawing Sheets
